ROAD JOINTS AND METHOD OF PRODUCING
SAME

Joseph William Heltzel, Warren, Ohio

Original application March 11, 1926, Serial No.
93,977. Divided and this application February
16, 1928, Serial No. 254,852

2 Claims. (Cl. 94—45)

The present invention relates to the building of concrete roads or other concrete surfacing structures, and the invention aims to provide a novel method of controlling the breaking or fracturing of the concrete after it has set, and such method may also be used for making traffic lines and joints in concrete roads or other surfacing structures.

As well known, roads and other surfacing structures composed of concrete will crack along irregular lines due to traffic or climatic changes, and a concrete road will usually become fractured along irregular lines lengthwise thereof due to the pressure and weight on the opposite side portions of the road under heavy traffic, and also due to the heaving action of the ground or sub-base in freezing weather. To overcome the irregular breaking of the concrete it has been the practice to install longitudinal vertical division plates along the line where the break is desired. These division plates are somewhat expensive, being embedded in the concrete, and extending from the sub-base to a point close to or at the surface of the concrete. It has been a difficult problem to install such division plates along a straight or regular line, and even with the use of such division plates an irregular break occurs, which, however, is not quite as objectionable as a natural break.

With the foregoing objections in view, it is an object of the present invention to control the breaking of the concrete or to make a joint in the concrete which will be less expensive and more effective than the use of division plates as heretofore. With those ends in view, division plates or strips are used which are of less height than the division plates heretofore used, to provide for economy, and to space the upper edges of the division plates or strips several inches below the surface of the concrete. These division plates or strips may also be installed more quickly, with a saving in cost, inasmuch as they need not be accurately disposed on the sub-base. This obtains a saving both in material and in installation, and, moreover, the division plates or strips do not interfere with the tamping or finishing off of the concrete above the division plates, as has occurred with the use of the ordinary division plates that extend to or adjacent the surface of the concrete. The invention consists further in forming a groove in the surface of the concrete above the division plates or strips. This groove may be formed quickly and accurately, so as to present a regular and accurate line, for purpose of appearance. After the concrete has hardened,

it will break between the groove and division plates or strips, said groove weakening the concrete above the division plates or strips so that the concrete, in cracking, will break along the line of the groove, which is the line of least resistance in the fracturing of the concrete. In this way, the breaking or fracturing of the concrete is controlled, for producing a joint in the concrete which may also serve as a traffic line for dividing oppositely moving traffic.

With the foregoing and other objects in view, which will be apparent as the invention is more fully understood, the invention resides in the method as hereinafter described and claimed, it being understood that changes may be made within the scope of what is claimed, without departing from the spirit of the invention.

The invention is illustrated in the accompanying drawing, wherein—

Figure 1 is a perspective view showing the several steps of the method employed and also illustrating the groove forming device in use.

Fig. 2 is a perspective view illustrating a modified form of division plate or strip.

Figs. 3 and 4 are cross-sections of completed joints showing modifications in the division plates or strips.

Although the invention is described in connection with the building of a concrete road, it will be understood that same may be used for other concrete surfacing structures for which the invention is suitable. When building a concrete road the side forms or rails 7 are disposed on the ground or sub-base to define the sides of longitudinal edges of the road, and the grout 90 is poured between said rails and the surface of the concrete finished in any well known manner.

In carrying out the present invention to control the longitudinal breaking of the concrete along the center line of the road, division plates 8 are placed on the sub-base along the line where the longitudinal break is desired. These strips 8 may be of thin sheet metal, so as to be inexpensive, and need only be of a height of two or three inches (more or less), so that their upper edges are spaced several inches below the surface of the concrete in the completed road. Such strips are therefore considerably cheaper than division plates heretofore used which extend from the sub-base to the upper surface of the concrete. It is unnecessary to locate the strips 8 along the desired line with extreme accuracy, so as not to require painstaking care in disposing said strips on the sub-base, thereby saving time as compared with the in-

stallation of ordinary division plates. The strips 8 are secured in place on the sub-base by means of stakes 9 driven into the sub-base, or other suitable means may be used for the purpose.

5 The strips 8 have sockets 10 through which the stakes are driven. The strips 8 may be plain, so as to be cheap, and may even be composed of wood, fibre, paper and other materials.

The positioning of the strips 8 on the sub-base 10 is the first step of the method and the next step consists in the pouring of the concrete on the sub-base between the rails 7 and over the strips. Said strips are placed on the sub-base in advance of the concrete mixer as it advances along the 15 roadway. The concrete is struck off, tamped and finished in any of the well known methods, and the strips 8 being located several inches below the surface of the concrete will not in any way interfere with the tamping and finishing of the 20 concrete over said strips, which has caused difficulty with the use of division plates extending close to the surface of the concrete. The strips 8 are embedded in the lower portion of the concrete 11, thereby dividing the concrete at the bottom thereof.

The third step in the method consists in forming a groove or cut 12 in the surface of the concrete above the strips 8. This groove 12 may be formed in the concrete while it is still plastic, and 30 it is possible to make the groove follow a definite straight or curved line, so as to produce a neat and finished job. This groove not only provides a traffic line along the center of the road for dividing oppositely moving traffic, but also controls, 35 in connection with the strips 8, the breaking of the concrete after the concrete has set. The concrete will break along the weakened portion between the strips 8 and groove 12, and even though the strips are not directly under the groove 12, 40 the breaks will extend upwardly from said strips to the groove 12 due to the weakening of the concrete by said groove. As a result, the concrete will break accurately along the groove 12 although the breaks may be irregular below said 45 groove. This irregular breaking of the concrete between the groove 12 and strips 8 is even of advantage in locking the adjacent edges of the opposite slabs or sections together against relative vertical displacement. The strips 8 being 50 cheaper in cost and less expensive to install as compared with the division plates heretofore used, will provide for economy, and the groove 12 may be quickly formed in the surface of the concrete. It is also apparent that the strips 8 may be 55 disposed transversely of the concrete with transverse grooves 12 above said strips, for producing transverse breaks or joints, and the strips and grooves may extend in different directions in various concrete surfacing structures for controlling 60 breaks and producing joints.

The appliance shown in Fig. 1 for producing the groove 13 is disclosed in Patent No. 1,726,665 granted September 3, 1929, of which this application is a division. Such appliance comprises a truck having the wheels 14 to move on

one of the rails, and the truck has a bar 18 carrying a trowel 20 provided with a longitudinal rib 24 to produce the groove 12 in the surface of the concrete. Such appliance or any other suitable device may be employed to produce the groove 12.

Fig. 2 illustrates a division plate or strip 8a having a plate 50 riveted or otherwise secured to one side thereof at each end, and said plates have the depending sharpened or pointed portions 51 to enter the ground, thereby providing end stakes or pegs to enter the ground for holding the ends of the plate or strip 8a in position. In order to hold the plate or strip 8a on the ground, a stake 9a is driven down into the ground at one side of the strip and has a hook 52 at its upper end to engage over the upper edge of the strip.

Fig. 3 illustrates the use of a division plate or strip 8b which is of curved cross-section, and which is preferably supported above the ground or sub-base, so that when the concrete sets it will break between the upper edge of said strip and the groove 12, and between the lower edge of said strip and the ground or sub-base, thereby forming the opposite slabs or sections with an interlocking tongue and groove defined by the 100 strip 8b. In order to support the strip 8b, the stake 9b which is driven into the ground may have an offset or seat 53 to support the strip, said strip having apertures through which the upper terminal of the stake passes.

Fig. 4 illustrates the stake 9b used with the strip 8 which is flat, for supporting the strip 8 above the ground.

Having thus described the invention, what is claimed as new is:—

1. The method of building a concrete road having a longitudinal joint, consisting in pouring the plastic concrete on a sub-base between side form rails, embedding longitudinal dividing means in the plastic concrete at a distance below the intended surface of the road, finishing the surface of the concrete and allowing the concrete to set partially, and then moving a grooving tool, while guided from one of said rails, over the surface of the concrete above said dividing means to 115 form a groove parallel with the corresponding side of the road and to determine the line of breakage of the concrete between said dividing means and the surface of the road.

2. The method of building a concrete road having a longitudinal joint, consisting in positioning division strips end to end above the sub-base of the road at a distance below the intended surface of the road and longitudinally of the road, pouring and finishing the concrete on said sub-base 130 over said strips between side form rails and permitting the concrete to set partially, and then moving a grooving tool, while guided from one of said rails, over the surface of the concrete above said strips to form a groove parallel with 135 the corresponding side of the road and to determine the line of breakage of the concrete from said strips to the surface of the road.

JOSEPH WILLIAM HELTZEL. 140
